C. P. H. WAGNER, OF NEW YORK, N. Y.

Letters Patent No. 64,814, dated May 14, 1867.

IMPROVEMENT IN COTTON AND HAY-PRESS.

The Schedule referred to in these Letters Patent and making part of the same.

TO ALL WHOM IT MAY CONCERN:

Be it known that I, C. PH. WAGNER, of the city, county, and State of New York, have invented a certain new and useful Improvement on Presses for Pressing and Baling Hay, Cotton, and other materials or substances, of which the following is a full, clear, and exact description, reference being had to the accompanying drawing forming part of this specification, and in which—

Figure 1 represents a sectional side elevation of a baling-press constructed according to my improvement.

Figure 2, a sectional side elevation of the same in part, viewed at right angles to fig. 1; and

Figures 3, 4, 5, 6, 7, 8, 9, 10, and 11, views of details detached.

Like letters indicate like parts throughout the several figures.

The nature of my invention consists in a novel construction and arrangement, in connection with toggle-joints, of worm segments forming what has been termed in other presses a close nut, by the same receiving in between them a vertical operating screw, said segments, in this my improvement, being constructed with intermediate radial arms, to which double or divided toggle-joints are pivoted to operate the platen, whereby not only is increased steadiness secured, but space economized, and first a slow, afterwards gradually quicker, and finally slower action, for a uniform velocity of the driving-shaft, given to the platen. Said invention also consists in a novel construction of baling-box provided with detachable side uprights fitting into shoes at their base, and gearing with open hook ends of a top cross-bar to the cover of said box, to prevent springing of the latter without restraining the opening of the same when required.

Referring to the accompanying drawing, A represents the uprights and cross-bars or frame of the press. Arranged at or near the base is a horizontal operating shaft, B, which may either be worked by hand or be rotated by or from any suitable power, by gearing or pulleys C C', thrown in or out of gear with the shaft B, to stop and start or reverse the motion of the press, by a clutch, a, worked by a lever or otherwise. This shaft B is carried in standards on a cross-brace or frame, b, and has mounted on its inner end a bevel-pinion, c, which serves to give motion, through a bevel-wheel, d, to a vertical screw, C, working in a step of the cross-brace b. If desired, a second operating shaft, with bevel-pinion attached, may be arranged on the opposite side of the vertical screw C, for working by hand on both or opposite sides of the wheel d. The vertical screw C is arranged to fit between, so as to gear with them, segments D D, provided with worm teeth on their edges or peripheries, said segments being on parallel horizontal shafts e e, resting in plumber-blocks, s, and having their edges or peripheries facing each other on opposite sides of the vertical screw, and forming, in conjunction, a nut to the screw C, as other segments for working presses have been used, but my construction and arrangement of such devices essentially differ from previous ones for the purpose, not simply in the position of their devices at or near the base where the action is steadier, and where the driving power is more readily available, as, for instance, where horse-power to work from the ground is employed, but furthermore differs in its connection with and operation of the toggle-joints to raise and lower the platen, that, in this case, lifts to effect the pressure, by constructing said segments with intermediate radial arms E, inclining downwards on starting to press, but projecting upwards when the pressure is completed, and so that the points of attachment of the toggle-joints to said arms and to the platen lie in the same vertical plane. F F' are the toggle-joints, made double, or divided on either side and connected by cross-pins f g to the arms E and platen G. The toggle-joints in being thus made double at either side, and which vibrate through slots h in the filling or packing-box H, not only give a steadier motion to the platen, and render unnecessary all extra or special guides to it, but admit of a longer throw within a given space or compass to said rods, and still preserve an equal thrust on opposite sides of the segments, which, in commencing to effect the lift, act upon the toggle-joints considerably below the segment shafts e e, as represented by black lines in fig. 1, and operate upon said toggle-joints till, in completing the pressure, they arrive at the position shown for them by red lines in the same figure. This range of action for the toggle-joints is not only a great economy of space in the working of the press, but by it the motion to the platen, with a uniform velocity of the operating shaft, is slow at starting, which gives time for adjusting the filling, and for air contained in the loose cotton or material to escape, and afterwards comparatively rapid, till towards the close of the pressing stroke, when the motion becomes gradually slower and more powerful to meet, as in other

toggle-joint actions, the increased resistance. Brace-rods *i i*, arranged on opposite sides of the frame, serve to strengthen the latter and tie the filling-box with the lower portion of the frame, and to these are hitched upper brace-rods *j j*, hooking at their upper ends, so as to be capable of easy removal on to the ends of cross-beams *k k*, secured on the top of the cover *I* of the baling-box, to which *J J* are the sides, and *K K*, are the end boards hung on lower hinges *l l*, and locked by hooks and catches *m m* and *n n*, to facilitate the opening and closing of the baling-box, the cover *I* of which, and platen *G*, are grooved as usual for passage of the baling-ropes. To prevent springing of the baling-box when it has been closed and locked against the pressure induced by the platen on the bale, a cross-bar, *L*, formed with open hook ends, is secured across the top of the cover *I*, for gear or lock, with upright side-braces *M*, fitting into shoes *o*, at their base, and with the hook ends of the cross-bar *L* at their upper ends so that the same may readily be detached when it is required to open the baling-box.

What I claim as my invention, and desire to secure by Letters Patent, is—

- What I claim as my invention, and desire to have patent rights in, is:

  1. The combination of the vertical screw C with the segments D D, provided with radial arms E, pivoted by double toggle-joints F F' to opposite sides or ends of the platen, operating so as to give to it a variable velocity and action, substantially as specified.
  2. The side-braces M, fitting into shoes o at their base, and gearing with open hook ends of a cross-bar, L, to the cover of the baling-box at top, essentially as shown and described.

C. PH. WAGNER.
